(57) **CLAIM**

The ornamental design for a trailer with a flexible bulkhead as shown and described.

DESCRIPTION

FIG. 1 is a right side elevation view of a first embodiment of a trailer with a flexible bulkhead in accordance with my design;

FIG. 2 is a right side elevation view of the trailer with a flexible bulkhead shown in FIG. 1;

FIG. 3 is a left side elevation view of the trailer with a flexible bulkhead shown in FIG. 1;

FIG. 4 is a rear elevation view of the trailer with a flexible bulkhead shown in direction of line 4-4 of FIG. 2;

FIG. 5 is a top plan view of the trailer with a flexible bulkhead shown in the direction of line 5-5 of FIG. 4;

FIG. 6 is a bottom plan view of the trailer with a flexible bulkhead shown in direction of line 6-6 of FIG. 4;

FIG. 7 is a top, rear, and left side perspective view of the trailer with a flexible bulkhead shown in FIG. 1;

FIG. 8 is a right side elevation view of a second embodiment of a trailer with a flexible bulkhead in accordance with my design;

FIG. 9 is a right side elevation view of the trailer with a flexible bulkhead shown in FIG. 8;

FIG. 10 is a left side elevation view of the trailer with a flexible bulkhead shown in FIG. 8;

FIG. 11 is a rear elevation view of the trailer with a flexible bulkhead shown in direction of line 11-11 of FIG. 9;

FIG. 12 is a top plan view of the trailer with a flexible bulkhead shown in direction of line 12-12 of FIG. 11;

FIG. 13 is a bottom plan view of the trailer with a flexible bulkhead show in direction of line 13-13 of FIG. 11; and,

FIG. 14 is a top, rear, and left side perspective view of the trailer with a flexible bulkhead shown in FIG. 8.

The broken lines illustrate portions of the trailer with a flexible bulkhead which form no part of the claimed design. The claimed trailer with a flexible bulkhead is shown with a symbolic break in its length. The appearance of any portion of the trailer with a flexible bulkhead between the break lines forms no part of the claimed design.
